GARMENT AND LIKE PRESSING MACHINE

Terence Herriot O'Brien, Kendal, England, assignor to Isaac Braithwaite & Son Engineers Limited, Kendal, England

Application October 19, 1938, Serial No. 235,839
In Great Britain October 28, 1937

5 Claims. (Cl. 38—40)

The invention relates to power operated garment pressing machines of the type in which a swivelling pressing head is carried by an arm mounted on a fulcrum shaft journalled in the frame and is brought into operation or pressing contact with a stationary "buck" or pad.

The object of the invention is to provide a pressing machine of the aforesaid type and particularly when operated by hydraulic means whereby a small pressure will be exerted during the movement of the pressing head into or almost into contact with the buck and a greatly increased pressure will be exerted during the final pressing operation.

The invention will be fully described with reference to the accompanying drawings:

Fig. 1 is a front elevation of the apparatus part in section.

Fig. 2 is a side elevation of the apparatus showing the head full open.

Fig. 3 is a side elevation showing the head 1 closed to within approximately one inch of the buck 2.

Fig. 4 is a side elevation showing the head 1 fully closed in contact with the buck 2.

Fig. 5 is a sectional plan through cylinder and piston slide valve on line 5—5 Fig. 4.

Fig. 6 is a side elevation of pumping unit detached.

Fig. 7 is a wiring diagram for solenoid.

The swivelling head 1, the "buck" 2 the arm 3 by which the head 1 is carried and the fulcrum shaft 4 journalled in bearings 5 of the frame are of conventional or known form.

In carrying out the invention a pair of cams or cam levers A are secured to the fulcrum shaft 4 one at either side of the frame, each cam lever being constructed with a face *a* concentric with the shaft 4 and a face *a*¹ radial or at an angle thereto. Below the cam levers A an hydraulic cylinder H¹ is mounted with piston H and piston rod J projecting upwards the cylinder H¹ being bolted inside an oil sump H² from which oil is pumped into the cylinder through the pipe D¹ and into which it returns through the exhaust ports.

A filbore or guide block K is attached to the piston rod J of the piston H and carries a stud on the ends of which are mounted two rollers L working in vertical guideways M to take any lateral thrust and maintain the piston rod J vertical. A pair of connecting links N are pivoted by one end to the filbore K and by the other end at a point intermediate its length to a transverse differential lever O thus connecting

the lever O with the piston rod J and transmitting the movement of the piston thereto.

A pair of rollers P are mounted one at each end of a spindle at one end of the differential lever O to engage the underside of the concentric cam faces *a* of the cam levers A. A second pair of rollers R engaging respectively the vertical faces of a pair of guide ways S are mounted on the same spindle as the pair of rollers P so that the rollers P can only acquire a vertical and parallel motion due to any pressure on the piston H. The other end of the lever O is connected by an adjustable connecting rod T with the cam lever A at *a*². Thus the initial upward movement of the piston H moves the outer end of the lever O and connecting rod T upward while the other end remains stationary the rollers P resting against the concentric surface *a* and acting as a fulcrum to the lever O. The initial upward movement of the lever O causes the cam levers A the fulcrum shaft 4 and the arm 3 to rock about their centre to bring the head 1 downwards towards the buck 2. When the head 1 and buck 2 are almost in contact (say about one inch apart) the pair of rollers P reach the end of the concentric cam faces *a* (see Fig. 3) and further movement upwards of the piston H brings the rollers P off the concentric face *a* on to the radial or inclined face *a*¹ (see Fig. 4) allowing the rollers R to rise in their guide-way S, the face *a*¹ being at this point slightly inclined to the vertical. As the rollers P ride up the face *a*¹ a comparatively small pressure on the piston H is transformed into a substantially increased horizontal thrust due to the rollers R compelling the rollers P to move vertically against the inclined faces *a*¹ of the cam levers and so force the head 1 and buck 2 tightly together. Any wear of the padding on the head 1 or buck 2 is compensated for by additional movement of the two pairs of rollers P and R up the faces *a*¹.

Hydraulic pressure is transmitted to the piston H by a centrifugal impeller B in a pump casing D directly coupled to an electro-motor C oil being delivered under pressure through a piston slide valve G (see Fig. 5) which controls a number of ports admitting oil either to the bottom or top of the piston H. Oil is delivered to an inlet port E and distributed along a transfer port F to an annular clearance between the shoulders of the piston slide valve G. The position of the slide valve determines whether the oil pressure is delivered to the top of the piston H or to the bottom of the piston H. When supplying oil to the top of the piston H, the oil is delivered along the

transfer port F to the cylinder port communicating with the top of the piston, and the exhaust port is in direct communication with the bottom of the cylinder port communicating with the bottom of the cylinder H¹. The oil from the bottom of the cylinder H¹ is therefore ejected to the sump H² through the ports for re-circulation through the system. The exhaust port communicating with the top of the cylinder is closed by the piston slide valve, as is also the inlet to the annular recess from the transfer port to the bottom cylinder port. When the piston slide valve G is moved to supply oil to the underside of the piston H, the inlet and exhaust ports formerly open will be closed, and the corresponding ports then closed will be opened. The oil pressure is then admitted to the bottom of the cylinder and rejected from the top of the cylinder through the exhaust port to the sump.

The piston slide valve G may be operated by either manual, mechanical, hydraulic, or electric means. In the preferred form of the invention the piston slide valve G is operated by a solenoid G¹ connected to the spindle g¹ in such a manner that when the solenoid is energised it will move the piston valve G to the position to admit oil to the underside of the piston H to lower the press head I to its working position, and when the solenoid is de-energised the weight of the solenoid plunger or its equivalent will return the piston valve G to the position to admit oil to the top of the piston H when the oil pressure thereon will return the head I to its open position. The spindle g¹ of the piston slide valve is connected to the spindle of the solenoid.

The solenoid is controlled by push buttons and contact 1^a, 2^a, 3^a and contacts 4^a shown on the wiring diagram Fig. 7. Two contacts 1^a and 3^a remain open when the press is open or out of use and in order to close the circuit and energise the solenoid both buttons 1^a and 3^a must be pressed. When the circuit is closed the oil pressure is delivered to the underside of the piston, the press is closed, and at a point immediately before the contacting position of the head I and buck 2 the pair of electric contacts 4^a will come together and maintain the solenoid in an energised condition thereby maintaining the pressure on the underside of the piston H after the two buttons 1 and 3 are released by the operator. The contacts 1^a and 3^a are so positioned as to require both hands of the operator preventing possibility of the operator's hands becoming trapped under the falling head. The pressing of the button and breaking the contact 2^a deenergises the solenoid, causing the solenoid plunger to fall, thus bringing the piston valve G into such a position that the oil pressure is transmitted to the top of the piston H causing the head I to rise. During closure of the head I, should the point at which contacts 4^a engage not be reached, when the operator releases either of the two closing buttons 1^a or 3^a the solenoid will become de-energised and the piston valve will again move to a position as to cause the oil pressure to operate on top of the piston, thus raising the head I.

In operation when the rollers P reach the inclined surface a¹ of the cam lever A the contacts 4^a are closed by a contact on the moving arm 3 and maintain the solenoid in an energised condition, thereby maintaining the pressure on the underside of the piston H, after the two buttons 1^a and 3^a are released by the operator. When the pressing operation is finished the button 2^a is depressed the solenoid circuit is broken, the sole-

noid becomes de-energised, solenoid plunger 1^a turns the piston valve G to the normal position and the piston H descends under the influence of pressure on the upper surface of the piston H. During this descent of the piston H, the rollers P are withdrawn down the inclined faces a¹ of the cam levers A, the rollers R fall in the slides S and come in contact with a stop U preventing them from descending further. At this point the concentric faces a of the cam levers A are capable of sweeping over the top of the pair of rollers P and as the piston H continues to descend the differential lever O will swing the cam levers round to raise the head I away from the buck 2.

15 A tie rod V is connected from the upper ends of the guide-ways M and S to the press framing to stiffen the guide-ways against deflection due to the pressure exerted by the wedging action of the rollers P against the inclined faces a¹ of the cam levers A.

The cam levers A are virtually integral with the pressing head I adjustment being provided to ensure that contact between the head I and the buck 2 can be assured at the precise moment when the pair of rollers P are moving up the inclined faces a¹ of the cam levers. When the setting of the cam levers A has been made by screw or other adjustment the head arm 3 and the cam levers are locked together.

25 30 The piston is preferably operated by oil as the pressure medium supplied from a sump H² to the intake of a centrifugal pump D and returned from the exhaust of the working cylinder H to the sump through the pipe D¹.

35 30 The centrifugal pump D may be driven mechanically from any source of power. Or any type of pump may be substituted for a centrifugal impeller.

40 What I claim as my invention and desire to protect by Letters Patent is:

1. In a garment pressing machine of the type in which a swivelling pressing head is carried by an arm secured on a fulcrum shaft journaled in the frame of the machine and is brought into pressing contact with a stationary buck, the combination with the pressing head of a cam shaped lever affixed on the fulcrum shaft and having two faces, one concentric with the fulcrum shaft and the other inclined to the first face and providing a cam surface, a connecting rod pivoted at one end on the cam lever by which the latter is oscillated to impart movement to the fulcrum shaft to actuate the pressing head, a pivot on the other end of the connecting rod, a differential lever pivotally mounted at one end on said pivot, a roller carried by the other end of the differential lever and engaging the faces of the cam lever, means to constrain the linear movement of the roller and therefore of the end of the differential lever to a vertical direction, a link pivoted at one end to the differential lever at a point intermediate of the ends of the latter and means connected to the other end of the link for imparting a linear movement thereto to cause a movement to be imparted through the differential lever to the connecting rod to actuate the pressing head, the face of the cam lever concentric with the fulcrum shaft being of such a length that the roller carried by the differential lever remains in contact therewith until the pressing head has almost engaged the buck whereby the roller will not move in a linear direction and the end of the differential lever to which it is attached will remain stationary until the pressing head has nearly engaged the buck, the movement imparted to the

differential lever by the link during such period of the operation being an oscillatory one about the axis of the roller, and the other face of the cam lever being at such angle to the first face that it will be at an inclination to the vertical when the pressing head has almost engaged the buck whereby when the roller passes from one face to the other, since its movement is limited to a vertical direction, it will exert a lateral pressure on the cam lever which pressure will be considerably in excess of the force exerted through the differential lever and connecting rod for actuating the cam lever and pressing head during the movement of the latter from its open position until almost in engagement with the buck.

2. In a garment pressing machine of the type in which a swivelling pressing head is carried by an arm secured on a fulcrum shaft journalled in the frame of the machine and is brought into pressing contact with a stationary buck, the combination with the pressing head of a cam shaped lever affixed on the fulcrum shaft and having two faces, one concentric with the fulcrum shaft and the other inclined to the first face and providing a cam surface, a connecting rod pivoted at one end on the cam lever by which the latter is oscillated to impart movement to the fulcrum shaft to actuate the pressing head, a pivot on the other end of the connecting rod, a differential lever pivotally mounted at one end on said pivot, a roller carried by the other end of the differential lever and engaging the faces of the cam lever, a second roller also carried on the end of the differential lever adjacent to the first roller, a vertical guideway in which the second roller moves thereby constraining the movement of the first roller and the end of the differential lever on which it is mounted to a vertical direction, a link pivoted at one end to the differential lever at a point intermediate of the ends of the latter and means connected to the other end of the link for imparting a linear movement thereto to cause a movement to be imparted through the differential lever to the connecting rod to actuate the pressing head, the face of the cam lever concentric with the fulcrum shaft being of such a length that the roller carried by the differential lever remains in contact therewith until the pressing head has almost engaged the buck whereby the roller will not move in a linear direction and the end of the differential lever to which it is attached will remain stationary until the pressing head has nearly engaged the buck, the movement imparted to the differential lever by the link during such period of the operation being an oscillatory one about the axis of the roller, and the other face of the cam lever being at such angle to the first face that it will be at an inclination to the vertical when the pressing head has almost engaged the buck whereby when the first roller passes from one face to the other, since its movement is limited to a vertical direction, it will exert a lateral pressure on the cam lever which pressure will be considerably in excess of the force exerted through the differential lever and connecting rod for actuating the cam lever and pressing head during the movement of the latter from its open position until almost in engagement with the buck.

3. In a garment pressing machine of the type in which a swivelling pressing head is carried by an arm secured on a fulcrum shaft journalled in the frame of the machine and is brought into pressing contact with a stationary buck, the combination with the pressing head of a cam shaped

lever affixed on the fulcrum shaft and having two faces, one concentric with the fulcrum shaft and the other inclined to the first face and extending from one end thereof toward the fulcrum shaft to provide a cam surface, a connecting rod pivoted at one end on the cam lever by which the latter is oscillated to impart movement to the fulcrum shaft to actuate the pressing head, a pivot on the other end of the connecting rod, a differential lever pivotally mounted at one end on said pivot, a roller carried by the other end of the differential lever and engaging the faces of the cam lever, a second roller also carried on the end of the differential lever adjacent to the first roller, a vertical guideway in which the second roller moves thereby constraining the movement of the first roller and the end of the differential lever on which it is mounted to a vertical direction, a link pivoted at one end to the differential lever at a point intermediate of the ends of the latter, an hydraulic cylinder, a piston therein and piston rod affixed thereto and connected to the other end of said link the movement of the piston within the cylinder being transmitted by the piston rod and link through the differential lever and connecting rod to actuate the pressing head, the face of the cam lever concentric with the fulcrum shaft being of such a length that the first roller carried by the differential lever remains in contact therewith until the pressing head has almost engaged the buck whereby the first roller will not move in a linear direction and the end of the differential lever to which it is attached will remain stationary until the pressing head has nearly engaged the buck, the movement imparted to the differential lever by the link, during such period of the operation being an oscillatory one about the axis of the first roller, and the other face of the cam lever being at such angle to the first face that it will be at an inclination to the vertical when the pressing head has almost engaged the buck whereby when the first roller passes from one face to the other, since its movement is limited to a vertical direction, it will exert a lateral pressure on the cam lever which pressure will be considerably in excess of the force exerted through the differential lever and connecting rod for actuating the cam lever and pressing head during the movement of the latter from its open position until almost in engagement with the buck.

4. In a garment pressing machine of the type in which a swivelling pressing head is carried by an arm secured on a fulcrum shaft journalled in the frame of the machine and is brought into pressing contact with a stationary buck, the combination with the pressing head of a cam shaped lever affixed on the fulcrum shaft and having two faces, one concentric with the fulcrum shaft and the other inclined to the first face, a connecting rod pivoted at one end on the cam lever by which the latter is oscillated to impart movement to the fulcrum shaft to actuate the pressing head, a pivot on the other end of the connecting rod, a differential lever pivotally mounted at one end on said pivot, a roller carried by the other end of the differential lever and engaging the faces of the cam lever, a second roller also carried on the end of the differential lever adjacent to the first roller, a vertical guideway in which the second roller moves thereby constraining the movement of the first roller and the end of the differential lever on which it is mounted to a vertical direction, a link pivoted at one end to the differential lever at a point intermediate of the ends of the latter, an hy-

draulic cylinder, a piston therein and a piston rod affixed thereto and connected to the other end of said link the movement of the piston within the cylinder being transmitted by the piston rod and link through the differential lever and connecting rod to actuate the head and a slide valve controlling the supply of fluid to the hydraulic cylinder, the face of the cam lever concentric with the fulcrum shaft being of such a length that the roller carried by the differential lever remains in contact therewith until the pressing head has almost engaged the buck whereby the roller will not move in a linear direction and the end of the differential lever to which it is attached will remain stationary until the pressing head is nearly closed, the movement imparted to the differential lever by the link during such period of the operation being an oscillatory one about the axis of the roller, and the other face of the cam lever being at such angle to the first face that it will be at an inclination to the vertical when the pressing head has almost engaged the buck whereby when the roller passes from one face to the other, since its movement is limited to a vertical direction, it will exert a lateral pressure on the cam lever which pressure will be considerably in excess of the pressure exerted through the differential lever and connecting rod for actuating the cam lever and pressing head during the movement of the latter from its open position until almost in engagement with the buck.

5. In a garment pressing machine of the type in which a swivelling pressing head is carried by an arm secured on a fulcrum shaft journalled in the frame of the machine and is brought into pressing contact with the stationary buck the combination with the pressing head of a pair of cam shaped levers affixed on the fulcrum shaft, one at each side of the machine, each cam lever having two faces, one concentric with the fulcrum shaft and the other inclined to the first face, a connecting rod pivotally connected at one end to the cam levers by which the latter are

10 oscillated to impart movement to the fulcrum shaft to actuate the pressing head, a pivot on the other end of the connecting rod, a differential lever pivotally mounted at one end on the said pivot, a pair of rollers mounted on the other end of the differential lever, one roller engaging the faces of one cam lever and the other roller the faces of the other cam lever, means to constrain the linear movement of the rollers and therefore of the end of the differential lever to a vertical movement, a link pivoted at one end to the differential lever at a point intermediate the ends of the latter and means connected to the other end of the link for imparting a linear movement thereto to cause a movement to be imparted through the differential lever to the connecting rod to actuate the pressing head, the faces of the cam levers concentric with the fulcrum shaft being of such a length that the rollers carried by the differential levers remain in contact therewith until the pressing head has almost engaged the buck whereby the rollers will not move in a linear direction and the end of the differential lever to which they are attached will remain stationary until the pressing head is nearly closed, the movement imparted to the differential lever by the link during such period of the operation being an oscillatory one about the axis of the roller, and the other faces of the cam levers being at such angle to the first faces that they will be at an inclination to the vertical when the pressing head has almost engaged the buck whereby when the rollers pass from one face to the other, since their movement is limited to a vertical direction, they will exert a lateral pressure on the cam levers which pressure will be considerably in excess of the pressure exerted through the differential lever and connecting rod for actuating the cam lever and pressing head during the movement of the latter from its open position until almost in engagement with the buck.

TERENCE HERRIOT O'BRIEN.
